(57) **CLAIM**

The ornamental design for an asymmetric linear optic, as shown and described.

DESCRIPTION

FIG. 1 is a perspective view, from above, of a first embodiment of an asymmetric linear optic;

FIG. 2 is a perspective view, from below, of the asymmetric linear optic of FIG. 1;

FIG. 3 is a right side elevation view of the asymmetric linear optic of FIG. 1;

FIG. 4 is a left side elevation view of the asymmetric linear optic of FIG. 1;

FIG. 5 is a rear elevation view of the asymmetric linear optic of FIG. 1;

FIG. 6 is a front elevation view of the asymmetric linear optic of FIG. 1;

FIG. 7 is a top plan view of the asymmetric linear optic of FIG. 1;

FIG. 8 is a bottom plan view of the asymmetric linear optic of FIG. 1;

FIG. 9 is a perspective view, from above, of a second embodiment of an asymmetric linear optic;

FIG. 10 is a perspective view, from below, of the asymmetric linear optic of FIG. 9;

FIG. 11 is a right side elevation view of the asymmetric linear optic of FIG. 9;

FIG. 12 is a left side elevation view of the asymmetric linear optic of FIG. 9;

FIG. 13 is a rear elevation view of the asymmetric linear optic of FIG. 9;

FIG. 14 is a front elevation view of the asymmetric linear optic of FIG. 9;

FIG. 15 is a top plan view of the asymmetric linear optic of FIG. 9; and,

FIG. 16 is a bottom plan view of the asymmetric linear optic of FIG. 9.

Features shown in broken lines in FIGS. 1-8 illustrate portions of the asymmetric linear optic that form no part of the claimed design. In FIGS. 9-12, 15 and 16, the broken line symbolic breaks and accompanying bracket indicate that the appearance of the asymmetric linear optic between the break lines forms no part of the claimed design.

1 Claim, 10 Drawing Sheets
